CLAIM

The ornamental design for a cutlery block with spice jar openings, as shown and described.

DESCRIPTION

FIG. 1 is a side, top perspective view of a cutlery block with spice jar openings showing our new design, the knife blade receiving slots shown in broken lines for illustrative purposes only and forming no part of the claimed design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a side, top perspective view of an alternate embodiment of FIG. 1 the difference being in the differently sized openings of the knife slots;

FIG. 9 is a top plan view of FIG. 8; and,

FIG. 10 is a right side elevation view of FIG. 8 the spice jars shown in broken lines for illustrative purposes only and forming no part of the claimed design.
